UNITED STATES PATENT OFFICE.

HARRY A. MULVANY, OF BERKELEY, CALIFORNIA, ASSIGNOR TO ELECTRIC SALES SERVICE COMPANY, OF SAN FRANCISCO, CALIFORNIA, A CORPORATION OF CALIFORNIA.

WALL INSERT ELECTRIC HEATER.

Application filed February 2, 1927. Serial No. 165,257.

This invention relates to electric heaters of the wall insert type such as employed for room heating and the like.

The object of the present invention is to generally improve and simplify the construction and operation of electric heaters; to provide an electric heater which will not only serve the function of a radiant heater, but also that of heating and circulating air; to provide an electric heater which may be readily inserted in the wall of a building; to provide means for rigidly securing the heating elements and their supports with relation to the heater frame; and further to provide means whereby the heating elements and their supports may be efficiently insulated to prevent conduction losses to the heater frame and casing and to reduce fire danger to a minimum.

One form which the heater may assume is shown by way of illustration in the accompanying drawings in which

Fig. 1 is a perspective view of the electric heater.

Fig. 2 is a perspective view of one of the heating element supports, this view also showing the manner of applying the heating element.

Fig. 3 is a rear view of the heater, showing the insulating member removed.

Fig. 4 is a vertical central cross-section taken on line IV—IV—Fig. 1.

Fig. 5 is a cross-section of the heater taken on line V—V Fig. 1.

Referring to the drawings in detail and particularly Figs. 1, 3 and 4, it may be stated that the heater consists of three main parts, to wit, a wall insert box A, a frame or face plate B and a grille C. The wall insert box is nothing more or less than a square or rectangular-shaped box constructed of sheet iron or like material consisting of a back section 2, side and end sections 3 and 4, and a flange 5. The front face 45 of the box is open and is adapted to receive the main frame or face plate B and the members carried thereby. The wall insert box is secured in the wall of a building in the usual manner. For instance, by securing the flange 5 to the studding of the wall structure. The main frame B is square or rectangular in shape as shown in Figs. 1 and 3. Its central portion is provided with a square or rectangular-shaped opening D

and it is also provided with upper and lower 55 rows of slots such as indicated at 6 and 7, the function of which will hereinafter be described. The main frame B serves a number of functions—

First—that of a support for the heating 60 elements, hereinafter to be referred to.

Secondly—that of a support for the insulation whereby conduction losses are reduced to a minimum.

Third—that of supporting a switch where- 65 by the circuit through the heating elements is circulated.

Fourth—that of supporting the grille C, and

Fifth—that of forming a closure for the 70 wall insert box A and at the same time to produce an ornamental effect.

The face plate B in the main frame is provided with inclined inwardly extending top and bottom flanges such as shown at 8 and 75 9. It is also provided with side flanges 10 and 11. The side flanges 10 and 11 are disposed at substantial right angles to the face of the frame B and they are extended inwardly some distance so as to form guides 80 and retaining members for the heating element supports, generally indicated at E; and also to form a support for an insulating plate, generally indicated at 31 (see Figs. 4 and 5).

The heating element supports are perhaps best illustrated in Figs. 1 and 2. They consist of rectangular-shaped blocks constructed of a refractory material and consisting of a back 14, a pair of head or end members 15 90 and a plurality of projecting interspaced ribs 16. These ribs are also interspaced with relation to the head members 15 and their upper and lower ends are provided with projecting lugs 17 which serve the function of 95 retaining the heating elements against displacement. The heating element supports or blocks shown in Fig. 2 do not form any part of this invention as they are fully described in my co-pending application entitled "Heating element support," filed 12—22—1926, Ser. No. 156,325. Sufficeth to say, however, that a number of these blocks are placed side by side across the opening D in the main frame as shown in Figs. 1 and 3, 100 105 there being four such blocks in the present instance and the blocks are of such a width that they will substantially fill the space

between the side flanges 10 and 11, and as this is the case, the blocks or heating element supports will be secured against lateral movement. Means must also be employed 5 for securing the blocks against endwise movement. The means illustrated in the present instance are a pair of bars 18. These bars are secured to the upper and lower ends of the side flanges 10 and 11 by means of 10 screws 19, and the blocks are thus rigidly secured both against lateral and endwise movement with relation to the opening D in the main frame or face plate B. By referring to Fig. 4, it will be noted that the head 15 members 15 of the respective blocks rest on the inner ends of the top and bottom flanges 8 and 9, and that the ribs 16 project through the opening D. The heating element employed is preferably of the ribbon type and 20 the ribbon, usually constructed of nichrome metal, is preferably wound in zigzag fashion between the ribs as shown in Fig. 2, and it is retained against displacement by the upper and lower lugs 17. The side flanges 10 25 and 11 are slotted as indicated at 21, and the slotted portions are covered by insulated blocks 22 which are secured to the side flanges 10 and 11 by means of screws 33. Each insulating block carries a terminal 30 connector 24. The ends of the nichrome ribbon are passed through the slots 21 and connected with the inner ends of the terminal screws while the outer ends of the terminal screws are connected with the circuit wires 35 25 and 26. These are in turn connected with a switch 27 in any ordinary manner, and the circuit through the heating elements will thus be closed or broken as desired.

The refractory material from which the 40 heating element supports or blocks E are constructed, is a fairly poor heat conductor, but, even so, it is found that the blocks gradually assume a temperature substantially equal to that of the ribbon elements carried 45 thereby. The temperature reached often approximates 1500 to 1600 degrees F., and care must accordingly be taken to reduce conduction losses to a minimum as the efficiency of the heater from a practical point of view 50 depends upon the amount of heat transferred to the atmosphere of the room. Care must also be taken that too much heat is not radiated or conducted to the wall insert casting A as fire danger is encountered. To reduce the conduction and radiant losses from 55 the heating element supports or blocks E to a minimum, one or more layers of asbestos or the like is placed rearwardly on the blocks crosswise of the side flanges 10 and 11 as indicated at 30, and on top thereof is placed a 60 polished plate 31. The plate and the asbestos insulating material is secured in position and against displacement by a series of screws such as shown in 32 which extend in- 65 to the ends of the side flanges 10 and 11,

said flanges being provided with tapped holes 33 for their reception. Conduction losses are thus reduced to a minimum, the heating element supports or blocks E are secured against inward displacement, and fire 70 danger is also reduced to a minimum as a comparatively small amount of heat is conducted through the asbestos and the plate 31. Such heat as may be conducted thereto is, however, dissipated as a space is left between the bottom of the wall insert box and the plate 31 which permits a continuous circulation of air. This air enters through the lower slots 7 in the direction of arrow a. This air passes upwardly and finally discharges through the upper slots 6 in the direction of the arrow b. The amount of air thus circulated is, however, comparatively small as a fairly small portion of the heat liberated passes through the plate 31. The 80 sides of the insert box are similarly protected as the air entering the slots 7 will also rise upwardly through the end passages indicated at 35, this air also discharging through the upper slots 6. The main air circulation is obtained from the face of the heater. That is, air passes between the grille and the heating elements in the direction of arrow c and as such circulation is continuous 85 while the heater is in operation, great quantities of air is heated.

With the use of ribbon elements held by blocks or supports of the character described, it is possible to eliminate metallic reflectors and the like, as the ribs and surface of the 100 blocks diffuses the radiant energy. This is also important as the radiant energy does not become sufficiently concentrated so as to cause scorching or overheating of furniture and the like placed in the immediate vicinity as is usually the case where reflector types of heaters are employed. The present heater diffuses the radiant energy in practically every direction and as such produces a beneficial effect, and at the same time presents a rather attractive glowing surface. The heater accordingly serves the function 110 of circulating and heating air, and also that of projecting radiant energy. The entire construction is exceedingly simple and substantial. The grille indicated at C protects the heating elements and also prevents accident by too close an approach. The general construction is exceedingly simple and installation may be affected wherever an 115 opening can be formed in the wall.

While certain features of the present invention are more or less specifically described and indicated, I wish it understood 120 that various changes may be resorted to within the scope of the appended claims. Similarly that the materials and finish of the several parts employed, may be such as the manufacturer may dictate or varying 125 conditions or uses may demand.

Having thus described my invention, what I claim and desire to secure by Letters Patent is—

1. In a heater of the character described, a frame consisting of a plate forming the front of the heater and provided with a central opening, said plate being also provided at the top and bottom of the opening with inclined flanges, blocks abutting 10 against the rear edges of the inclined flanges and adapted to support heating means, and resilient clamping strips carried by the said plate and extending across the same at the top and bottom of the opening thereof, and 15 engaging the blocks at the top and bottom thereof.

2. In a heater of the character described, a frame consisting of a plate forming the

front of the heater and provided with a central opening, said plate being also provided at the top and bottom of the opening with inclined flanges and having vertical flanges at the sides of the opening, blocks located between the side flanges and abutting against the inclined flanges, resilient 20 clamping strips mounted on the side flanges and extending across the space between the same and engaging the blocks at the top and bottom thereof, and the rear plate also supported by the said side flanges and arranged at the back of the blocks and confining the same between the clamping strips and in abutting relation with the inclined 25 flanges.

HARRY A. MULVANY.
